AIRCRAFT

William L. Weak, St. Louis, Mo.

Application May 21, 1958, Serial No. 50,998

Term of patent 14 years

(Cl. D71—1)

Fig. 1 is a top plan view of an aircraft showing my new design;

Fig. 2 is a side elevational view thereof with portions of the rotor blades broken away for convenience of illustration only;

Fig. 3 is a front elevational view of the aircraft; and
Fig. 4 is a rear elevational view thereof.

The dominant features of the design reside in the portions shown in full lines.

I claim:

The ornamental design for aircraft, substantially as shown and described.
